UNITED STATES PATENT OFFICE

2,543,695

FLEXIBLE ROOFING MATERIAL

Theodore H. Kashuba, East Liverpool, Ohio, assignor to T-K Roofing Manufacturing Company, Chester, W. Va., a corporation of West Virginia

Application January 27, 1947, Serial No. 724,679

4 Claims. (Cl. 108—7)

1

This invention relates to improvements in roofing material and is more particularly concerned with a composition roofing material of the type composed of a web of paper, felt, or other suitable fibrous material saturated and coated with asphalt and having one face thereof covered with suitable mineral granules, such as gravel, crushed stone, slate, etc. During the manufacture of composition roofing material, the present invention contemplates the provision of an embossing operation in which the finished material is inserted through a pair of embossing rolls which act to form longitudinally and transversely disposed stripes on the granular coated surface of the material to simulate the appearance of shingles when the roofing strips are laid in overlapping relation upon the roof of a building. The top edge portion of each strip of roofing material also has the granules pressed downwardly into and completely imbedded within the asphaltic coating material to provide a relatively smooth, tacky surface for lapping adhesive engagement with an overlaying strip, and it is an object of the present invention to form a longitudinally extending sealing ridge along said smooth tacky surface to coact with an overlying shingle strip to prevent leakage due to water being blown upwardly between overlapping strips.

It is a further object of this invention to provide a roofing strip which is embossed to form abutment shoulders to facilitate alignment of overlying roofing strips, the abutment shoulders being formed and arranged to form part of the shingle pattern during the laying of a roof.

It is a further object of this invention to provide an embossed design in which the ends of adjacent shingle simulations are defined by closely spaced parallel stripes which merge with spaced horizontally extending stripes and thus present a more realistic shingle effect than has heretofore been provided on roofing material.

It is a further object of this invention to provide a roofing material adapted to be formed into rolls suitable for shipping or storage, and in which the embossed tacky surface of the strip will not become adhesively united to adjacent convolutions within the roll.

It is a further object of this invention to provide an embossing roll with circumferential and longitudinal ribs for embossing the granular coated surface of the roofing strip, and to provide means for heating the embossing roll to cause the asphaltic material to flow and completely cover the granules as the latter are pressed into the strip material.

2

This invention embodies other novel features, details of construction and arrangement of parts which are hereinafter set forth in the specification and claims and illustrated in the accompanying drawing wherein:

Fig. 1 is a fragmentary plan view illustrating the method of applying the improved roofing strips to the roof of a building.

Fig. 2 is an enlarged transverse sectional view 10 taken along the line 2—2 of Fig. 1.

Fig. 3 is an enlarged fragmentary perspective view showing the sealing ridge and alignment shoulders formed on the depressed lap portion of a roofing strip.

Fig. 4 is a plan view showing the roofing material prior to being severed longitudinally to form two similar roofing strips.

Fig. 5 is a perspective view showing a roll for embossing the surface of the roofing strip.

20 Referring now to the drawings for a better understanding of this invention, a flexible roofing strip is shown as comprising a web 8 of felt, paper or other fibrous material saturated with asphalt or similar waterproofing material. The 25 outer or exposed surface of the web is provided with a weather-protective layer 9 of high melting point asphalt, or the like in which is partially imbedded a coating 11 of granular material, such as crushed slate, gravel, or the like.

Roofing strips of the type thus described have 30 heretofore been cut to length and rolled up ready for market. As the entire exposed surface of this type of roofing material presents a rather monotonous uniform color and appearance, the present invention contemplates the provision of 35 an improved method and apparatus for providing the exposed granular coated surface 11 with an ornamental and artistic appearance.

After the granular coating 11 is applied to the 40 strip or web 8, and while the protective layer 9 of asphalt is at a temperature of approximately 275° to 300° F., the strip is inserted between a pair of rolls to emboss the exposed granular surface 11 to simulate the appearance of shingles.

45 Fig. 5 in the drawings illustrates an embossing roll 12 which coacts with a smooth surfaced roll (not shown) to form depressed horizontal stripes 13 and depressed vertical stripes 14, the latter stripes being arranged in pairs, to produce on the 50 exposed surface of the strip 8 the effect of shingles laid in overlapping rows, as illustrated in Fig. 1. The exposed granular coated surface 11 of the strip is also depressed along one edge thereof at 16 to provide a lap edge for engagement under an 55 overlying strip. The depressed surface 16 form-

ing the lap edge is formed with a longitudinally extending sealing ridge 17 which is adapted to engage against the underside of an overlying strip to prevent the passage of water upwardly therebetween. Alignment projections 18 are disposed along the depressed surface 16 to project toward the adjacent edge of the strip a distance substantially equal to the width of the horizontal stripes 13 to facilitate alignment of overlying strips and to also carry out the appearance of equally spaced stripes 13 throughout a roof 19.

The roll 12 employed for embossing the granular coated surface 11 of roofing strips is formed with circumferential ribs 21 for forming depressed horizontal stripes 13 and with closely spaced axial extending ribs 22 for forming the depressed vertical stripes 14-14. One end of the roll 12 is formed with a raised circumferential portion 23 for forming the depressed surface 16 along one edge of the roofing strip, and a groove 24 is formed in the raised surface 23 to form the longitudinally extending sealing ridge 17. The inner edge of the raised portion 23 is notched at spaced intervals at 26 to form the alignment projections 18 at spaced intervals along the depressed surface 16 of the strip.

During the embossing operation, the granular coated strip is tightly compressed between the embossing roll 12 and its coacting smooth surfaced roll (not shown) to cause the raised surfaces on the embossing roll to press the granular coating into the weather-protective layer 9 of high melting point asphalt. During the embossing operation, the embossing roll 12 is heated to a suitable temperature by means of a gas flame to cause the asphalt to flow and completely cover the granular material along the depressed portions of the strip, the depressed portions are thus caused to present a black, smooth, tacky surface free of exposed granular material.

The strip is preferably formed from a sheet 31 approximately 36 or 37 inches in width, shown in Fig. 4, which is cut longitudinally along its center at 32 to provide two similar finished strips approximately 18 or 18½ inches in width and of any suitable commercial length. The width of 18-18½ inches is selected as this permits simulating the present most popular size of shingle. The stripes 13 and 14 define rectangular shingle-like formations 33 having a width of approximately 11½ inches and a height of approximately five inches, the horizontal stripes being approximately ⅜ of an inch wide, and the vertical stripes 14-14 being approximately ⅛ of an inch wide. The granular coated vertical strips 34, defined by each pair of vertical stripes 14-14, are approximately ⅜ of an inch wide. The alignment shoulders 18 are formed ⅜ of an inch in width to correspond with the width of the granular coated strips 34. The depressed lap surface 16 is approximately 2¼ to 2¾ inches in width, and the sealing ridge 17 is disposed approximately one inch from the edge of the strip and extends upwardly from the lap surface 16 approximately ⅛ of an inch.

The strips are applied to the roof of a building in overlapping relation with the lower edge of each strip above the first strip covering the depressed lap surface 16 of the adjacent lower strip. By forming an upstanding sealing ridge 17 extending along and projecting above the plane of the depressed surface 16, a sharp line contacting engagement is provided within each lap joint to prevent the passage of water upwardly between

adjacent strips. It has also been found that the heat rays from the sun causes the lap portion of adjacent strips to become adhesively united, and thus form a water-tight joint which is not readily broken by high velocity wind storms. It will further be noted that the alignment shoulders 18 provided at spaced intervals along the depressed lap surface 16 facilitate the alignment of adjacent strips during the mounting of strips upon a roof.

Another important feature of this invention resides in the provision of the granular coated vertical strips 34 defined by each pair of vertical stripes 14-14. After a roof has been covered by this type of roofing strips, it presents the same appearance as a shingle covered roof and has, therefore, been accorded a very favorable reception in the trade.

While this invention has been shown in but one form, it is obvious to those skilled in the art that it is not so limited but is susceptible of various changes and modifications without departing from the spirit and scope of the claimed invention.

I claim as my invention:

1. A building material comprising a strip of flexible waterproof material having one side thereof coated with asphalt and mineral granules, the coated side only of said strip being formed with depressed longitudinal and transverse stripes defining raised shingle formations, the other side of said strip being flat, said transverse stripes being arranged in pairs to define narrow raised coated surfaces between adjacent shingle formations, one edge of said strip being compressed to provide a smooth depressed lap surface for adhesive engagement with the lower edge of an overlying strip, and alignment shoulders formed on the upper row of said shingle formations and arranged at mid-points thereabove to project onto said depressed lap surface a distance substantially equal to the width of said longitudinal stripes.

2. A building material comprising a strip of flexible waterproof material having one side thereof coated with asphalt and mineral granules, the coated side only of said strip being formed with depressed longitudinal and transverse stripes defining raised shingle formations, the other side of said strip being flat, said transverse stripes being arranged in pairs to define narrow raised coated surfaces between adjacent shingle formations, one edge of said strip being compressed to provide a smooth depressed lap surface for adhesive engagement with the lower edge of an overlying strip, a sealing ridge extending along and projecting outwardly from said depressed lap surface for line engagement with the underside of an overlying strip, and alignment shoulders formed on the upper row of said shingle formations and arranged at mid-points thereabove to project onto said depressed lap surface a distance substantially equal to the width of said longitudinal stripes.

3. A building material comprising a strip of flexible waterproof material having one side thereof coated with asphalt and mineral granules, the coated side only of said strip being formed with depressed longitudinal and transverse stripes defining raised shingle formations, the other side of said strip being flat, said transverse stripes being arranged in pairs to define narrow raised coated surfaces between adjacent shingle formations, one edge of said strip being com-

pressed to provide a smooth depressed lap surface for adhesive engagement with the lower edge of an overlying strip, a sealing ridge extending along and projecting outwardly from said depressed lap surface for line engagement with the underside of an overlying strip, alignment shoulders formed on the upper row of said shingle formations and arranged at mid-points thereabove to project onto said depressed lap surface a distance substantially equal to the width of said longitudinal stripes, said alignment shoulders having a width substantially equal to the width of said narrow raised surfaces formed between adjacent shingle formations.

4. A building material comprising an elongated imperforate strip of flexible waterproof material having parallel edges one side thereof being coated with asphalt and mineral granules, the coated side only of said strip being formed with depressed longitudinal and transverse stripes defining raised shingle formations, the other side of said strip being flat, said transverse stripes being arranged in pairs to define narrow raised coated surfaces between adjacent shingle formations, one edge of said strip being embossed to provide a smooth depressed lap surface for adhesive engagement with the lower edge of an

overlying strip, a sealing ridge extending along and projecting outwardly from said depressed lap surface for line engagement with the underside of an overlying strip, said sealing ridge being substantially centrally disposed along said depressed lap surface and alignment shoulders formed on the row of shingles adjacent to said depressed lap surface and projecting onto the latter and being elevated therefrom and arranged at mid-points above said shingles and adapted to coincide with the vertical joints of a superimposed unit.
